DESIGN FOR A COFFEE POT

Ve Elizabeth Cadie, Alexandria, Va.

Application August 30, 1945, Serial No. 121,755

Term of patent 7 years

(Cl. D44—26)

To all whom it may concern:

Be it known that I, Ve Elizabeth Cadie, employee of the War Department, United States Government, a citizen of the United States, residing at 16 C Court Auburn Garden, Alexandria, Virginia, have invented a new, original, and ornamental Design for a Coffee Pot, of which the following is a specification, reference being had to the accompanying drawing, forming a part thereof.

I claim:

The ornamental design for a coffee pot, as shown.

VE ELIZABETH CADIE.
